UNITED STATES PATENT OFFICE.

EARL E. CARRÉ, OF CALDWELL, NEW JERSEY.

INFANT'S TOILET-CHAIR.

1,281,763.

Specification of Letters Patent. Patented Oct. 15, 1918.

Application filed March 30, 1917. Serial No. 158,640.

To all whom it may concern:

Be it known that I, EARL E. CARRÉ, a citizen of the United States, and a resident of Caldwell, in the county of Essex and State 5 of New Jersey, have invented a new and Improved Infant's Toilet-Chair, of which the following is a full, clear, and exact description.

This invention relates to a folding chair, 10 and particularly to an infant's toilet seat, and has for its general objects to improve the construction so as to be reliable and efficient in use, comparatively simple and inexpensive to manufacture and of such design 15 as to enable the chair or seat to be easily and quickly folded or unfolded and to take up comparatively little space when folded.

A more specific object of the invention is the provision of a folding chair having a 20 novel interlocking connection between the back and side or arm members.

Another object is to provide novel means whereby the chair or seat can be effectively held on a closet seat.

25 With such objects in view, and others which will appear as the description proceeds, the invention comprises various novel features of construction and arrangement of parts which will be set forth with particularity in the following description and 30 claims appended hereto.

In the accompanying drawing, which 35 illustrates one embodiment of the invention and wherein similar characters of reference indicate corresponding parts in all the views,

Figure 1 is a perspective view of the chair set up for use;

Fig. 2 is a rear view thereof;

40 Fig. 3 is a plan view showing the seat or chair with its leg members folded for application to a closet seat; and

Fig. 4 is a detail view showing the interlocking of the back and side members.

Referring to the drawing, 1 designates the 45 seat plate which has the usual central opening 2, and fastened to the side edges are narrow strips 3 that have hinged thereto the side or arm members 4. Connected by hinges 5 with the rear portion of the seat member 50 1 is a back 6 which is adapted to fold forwardly and downwardly on top of the seat member 1 and to slide between the strips 3 which are of substantially the same height as the thickness of the back 6. By this arrangement the side members can fold inwardly over the back when the latter is

folded down. As shown in Fig. 2, the side members 4 are held in upstanding position by means of collapsible braces 7 having knuckle joints 8, the braces being pivoted 60 at 9 and 10 to the arm members 4 and seat member 1, respectively. The braces are fixed to the rear edges of the said members and they lie behind the back 6, so as to prevent the latter from being sprung backwardly. 65 In other words, the braces 7 brace the side and back members when the same are in set-up position. The inner faces of the side members have recesses or shoulders 11, and the side edges of the back 6 have projections 70 12 which engage in the recesses 11, so that the back cannot move forwardly accidentally. In order to allow the back to fold forwardly the side members must be sprung or forced outwardly to disengage the projections 75 12 from the recesses 11.

On the inner faces of the side members are wearing strips 13 on which the projections 12 bear when the back is swung back and forth in folding or unfolding. 80

The chair or seat may be provided with leg frames which are adapted to fold under the seat member 1. Each frame comprises a horizontal bar 14, to the ends of which are fastened legs 16, the members 14 being connected by hinges 17 to the side edges of the seat member 1. Collapsible braces 18 fastened to the rear edge of the seat member 1 and to the rear legs as shown in Fig. 2, serve to hold the leg frames in vertical position. 85 The leg frames may be provided with suitable means for adjusting the chair to a toilet seat. For this purpose blocks 19 or equivalent means are fastened to the leg frames at their upper corners, so that when the leg frames are in folded position under the seat member these blocks will project downwardly and form lugs which will engage a toilet seat at four points *a*, Fig. 3, so that the infant's toilet seat may be effectively held in 90 place.

From the foregoing description taken in connection with the accompanying drawing, the advantages of the construction and method of operation will be readily understood by those skilled in the art to which the invention appertains, and while I have described the principle of operation, together with the device which I now consider to be the best embodiment thereof, I desire to 105 have it understood that the device shown is merely illustrative and that such changes 110

may be made when desired as fall within the scope of the appended claims.

Having thus described my invention, I claim as new and desire to secure by Letters

5 Patent:

1. An article of the class described comprising a seat member, a back member hingedly connected with the seat member to fold downwardly on top of the seat member, 10 side members hingedly connected with the seat member and adapted to fold downwardly on the back member, the upper rear corners of the side members having recesses in their inner faces, projections on the side 15 edges of the back member to engage in the said recesses to prevent forward movement of the back from an upright position when the side members are up, and braces located behind the back and hingedly connected with 20 the back edge of the seat member and hingedly connected with the rear edge of the

side members and extending across the lower corners of the back member to brace the latter against backward movement and for holding the side members with the recesses 25 thereof engaged with the projections of the back member.

2. An article of the class described comprising a seat member, a back hinged to swing forwardly on the seat member, strips 30 on the seat member of substantially the same thickness as the back, side members hinged on the said strips and adapted to fold down over the folded back member, collapsible braces pivotally connected with 35 the seat member and pivotally connected with the side members and adapted to extend across the lower corners of the back member when in raised position, and means on the back and side members adapted to be 40 held in engagement by the braces.

EARL E. CARRE.
